(57) **CLAIM**

The ornamental design for an AC condensate drain line evacuation adapter, as shown and described.

DESCRIPTION

FIG. 1 is a perspective view of an AC condensate drain line evacuation adapter of the instant invention;

FIG. 2 is a left side view thereof, the right side view (not shown) forming a mirror image thereof;

FIG. 3 is a front view thereof;

FIG. 4 is a back view thereof;

FIG. 5 is a top view thereof; and,

FIG. 6 is a bottom view thereof.

The dashed broken lines in the drawings depict portions of the article that form no part of the claim.
